UNITED STATES PATENT OFFICE.

PETER M. KLING, OF ST. LOUIS, MISSOURI.

STREET AND STATION INDICATOR.

SPECIFICATION forming part of Letters Patent No. 351,270, dated October 19, 1886.

Application filed March 6, 1886. Serial No. 194,296. (No model.)

To all whom it may concern:

Be it known that I, PETER M. KLING, of the city of St. Louis, in the State of Missouri, have invented a certain new and useful Improvement in Street and Station Indicators, of which the following is a full, clear, and exact description, reference being had to the accompanying drawings, forming part of this specification, and in which—

10 Figure 1 is a front or back view of my improved indicator, showing part of the casing broken away. Fig. 2 is a vertical section taken on line 2 2, Fig. 1.

My invention relates to an improved indicator, or, intended more particularly for use on street-cars for indicating the streets, but which may be used on steam-cars to indicate the stations; and my invention consists in features of novelty hereinafter fully described, and pointed 20 out in the claims.

Referring to the drawings, A represents a suitable case or box, in the upper end of which is journaled a shaft, B, having a hub, C, composed of four or more equal sides. Over the 25 hub C fits an apron, D, of chains, the length of the links of the chains being equal to the width of the hub C, as shown in Fig. 2.

F represents tablets secured to the chains, one being secured to each link; as shown in the 30 drawings; or, if necessary, only part of the links may be provided with the tablets. On turning the shaft it will be seen that the tablets are brought one after the other into a vertical position over the shaft B, as shown in Fig. 2. Upon these tablets are marked the names of the streets or stations—as, for instance, 35 the word "Pine"—as shown in Fig. 1.

The upper end of the box A is provided with an opening closed by a glass, E, through 40 which the occupants of the car can see the names on the tablets, thus being informed of the next street. The box also has an opening closed by a glass, G, in its other side, so that the driver can see that the device is operating 45 properly. I prefer to make in the top of the

case an opening closed by a glass, H, to admit light, so that the names on the tablets can be clearly seen.

The shaft B is turned to bring up the tablets, one after the other, by means of a suitable 50 crank, I, which is provided with a pawl, J, engaging a stationary ratchet-wheel, L. This prevents the shaft turning until the next time the crank is operated.

As each link is the length of one face of the 55 hub C the chain is kept from any movement until the shaft is turned, and each time the shaft is turned a tablet is brought (by a positive movement) in front of the glasses E and G.

I prefer to locate inside of the case a partition, M, around which the chain passes, and by which it is held in a vertical position, thus preventing it from being tangled.

I am aware that an upper and lower hub having an indicator-belt traveling around the 65 same is old, and also that it is old in station-indicators to divide the case by a partition attached to the lower part of the case, within each division of which is passed alternately back and forth a chain of indicator-tablets 70 passing over a revolving hub; but these constructions I do not desire to claim.

I claim as my invention—

1. In an indicator, the combination, with a 75 casing provided with observation-openings, of a single shaft journaled in the casing, a single hub thereon, a partition, and a belt provided with indicator-tablets and traveling over said hub and around said partition, being operated by said shaft, substantially as set forth. 80

2. In an indicator, the case provided with front and back openings, a single shaft provided with a single hub, a belt fitting upon the hub, and a partition around which the belt travels, substantially as and for the purpose 85 set forth.

PETER M. KLING.

In presence of—

GEO. H. KNIGHT,
JOSEPH WAHLE.
